(57) **CLAIM**

The ornamental design for a modular LED light housing for pole mounting, as shown and described.

DESCRIPTION

FIG. 1 is a perspective view of a first embodiment of a modular LED light housing for pole mounting;

FIG. 2 is a front elevational view thereof;

FIG. 3 is a rear elevational view thereof;

FIG. 4 is a left elevational view thereof, a right elevational view being a mirror image thereof;

FIG. 5 is a top plan view thereof; and,

FIG. 6 is a bottom plan view thereof;

FIG. 7 is a perspective view of a second embodiment of a modular LED light housing for pole mounting;

FIG. 8 is a front elevational view thereof;

FIG. 9 is a rear elevational view thereof;

FIG. 10 is a left elevational view thereof, the right elevational view being a mirror image thereof; and,

FIG. 11 is a top plan view thereof; and,

FIG. 12 is a bottom plan view thereof.
